(57) **CLAIM**

The ornamental design for a wireless network device, as shown and described.

DESCRIPTION

FIG. 1 is a front perspective view of a wireless network device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective thereof.

The dot-dashed broken lines depict boundaries of the claimed design and form no part thereof. The areas completely surrounded by dot-dash broken lines form no part of the claimed design.
